UNITED STATES PATENT OFFICE.

CHARLES E. HOPKINS, OF PLAINFIELD, NEW JERSEY.

SEMI-AUTOMATIC STEREOTYPE-PLATE CASTING AND COOLING MACHINE.

1,330,942.

Specification of Letters Patent. Patented Feb. 17, 1920.

Application filed May 15, 1914, Serial No. 838,647. Renewed July 5, 1919. Serial No. 308,834.

To all whom it may concern:

Be it known that I, CHARLES E. HOPKINS, a citizen of the United States, residing at Plainfield, in the county of Union and State 5 of New Jersey, have invented a new and useful Semi - Automatic Stereotype - Plate Casting and Cooling Machine, of which the following is a specification.

My present invention contains many improvements in the stereotype plate making art, among which are:

The arrangement of the casting mechanism so that the operator stands at the rear end to position the matrix, close the chamber, operate the pump to make a cast, open the casting chamber, strip the matrix free from the cast, inspect the cast and thereafter deliver it to the finishing mechanism; a concave back pivoted by one end to a support and a convex core pivoted near its center at right angles to its axis; means operated by the movement of the back to turn the core; means on the back independent of the matrix clamps for positioning a matrix; 25 means independent of both back and core for supporting a pouring sheet; means for moving the pouring sheet longitudinally away from the margin of the matrix; means operated by the back for moving the pouring sheet; means on the pouring sheet support for positioning the core; means carried by the core for simultaneously separating the bottom ring from the cast plate and the plate from the core and thereafter alining the 30 plate with a finishing mechanism; means by which the plate starts the mechanism through one cycle of operations; a plate positioning stop provided with means for starting the finishing mechanism through a 35 cycle and thereafter stop the same.

The invention also involves improvements in details of construction of the parts thereof.

Reference is to be had to the accompanying drawings in which

Figure 1 is a side elevation of the complete machine with the core turned to the delivering position, a cast plate being shown resting on the plate lifting roller, and over 50 the core;

Fig. 2 is a front side view of the casting mechanism showing the back in the open position and the core turned by the back supporting means;

55 Fig. 3 is a side elevation of the casting

mechanism, showing the casting members in closed position, the front side frame being removed;

Fig. 4 is a plan view of the casting mechanism in the closed position;

Fig. 5 is a longitudinal central section taken through the center of the casting member in closed position;

Fig. 6 is a front view of the same;

Fig. 7 is a sectional plan view of the parts 65 in the position shown in Fig. 3 and showing the matrix clamping, casting chamber locking, and plate lifting mechanism;

Fig. 8 is an enlarged fragmental end view of the core and back locking mechanism, 70 matrix positioning means and matrix clamping mechanism;

Fig. 9 is a plan view of the finishing mechanism with the finishing arch and its support removed, a portion of the shaving 75 knife shaft broken away, and the trimming mechanism sectioned;

Fig. 10 is a central longitudinal section of part thereof;

Fig. 11 is a cross section on line 11—11 of 80 Fig. 9;

Fig. 12 is a cross section on line 12—12 of Fig. 9;

Fig. 13 is a cross section taken at the end 85 of the arch in Fig. 9;

Fig. 14 is a cross section taken on line 14—14 of Fig. 9, showing the mechanism in position half way through its cycle.

Fig. 15 is a cross section on line 15—15 of Fig. 9;

Fig. 16 is a side view of one of the arch operating toggles, and associated parts;

Fig. 17 is a cross section of the same on line 17—17 of Fig. 16;

Fig. 18 is a side view of the arch support- 95 ing and positioning brackets with the arch plate rollers attached;

Fig. 19 is an end view thereof;

Fig. 20 is a central longitudinal sectional view of the cooling mechanism, and 100

Fig. 21 is a cross section thereof on the line 21—21 of Fig. 20;

The mechanism is shown as supported between side frames A and B, and cross frames C and D. The casting back 10 is 105 mounted on a pivot bracket 11 fast on a cross pivot shaft 12 which operates in bearings formed in the side frames A and B. A stop 13 is formed on the bottom of the bracket 11 which engages with a cross brace 110

14 fixed between the side frames. This stop holds the back up in the open position (see Fig. 2).

Counterbalance springs 15 are wound 5 about the pivot shaft 12. One end of each spring is fast in a collar 16 which is fast on the shaft and the other end engages against the cross brace 14. The springs are drawn up sufficiently to counteract the weight of 10 the back.

A locking strip 17 is mounted on each straight face of the back 10. The strip 17 is formed with a raised extension 18 projecting toward the axis of the back's concavity. A matrix bolster packing strip 19 15 is located beneath the raised extension 18 and rests upon the straight faces of the back. This packing strip is provided with a groove 21 in which a loose fitting tongue 20 formed on the under side of the strip 17 engages and holds the bolster packing strip in position, so that it can have a slight swinging movement. This is necessary to permit the plate to pass the loose end of 25 the bolster packing strip which protrudes slightly over the edge of the back's concavity. See Fig. 8.

For the purpose of positioning the matrix M in the concavity of the back and 30 holding it in curved position until the matrix clamps are brought into action, there are provided two matrix positioning slides 22 at each side of the back. The slides 22 are supported in angular grooves formed in 35 projections 24 which are located on top of the locking strips 17. These slides 22 are moved down their inclined grooves by the operator, over the top of the bolster packing strips, 19 and over the edge of a matrix located in the back's concavity. They 40 hold the matrix in curved position against the back's concavity. They are later pushed back by locking and matrix clamping bars carried by the core as hereinafter described.

45 See Figs. 7 and 8.

The segmental core 30 is mounted on brackets 31, 31, one of which is located on each of its straight edges. These brackets 31, 31 are held a distance away from the 50 core's straight face by positioning collars 32 (see Fig. 7). A pivoting yoke 33 is mounted in bearings formed in the side frames A and B. The yoke is provided with two seats 34, 34 fitted to like seats on 55 the core's brackets 31, 31. The yoke, brackets and collars are joined to the core by studs 35. See Figs. 6 and 7.

Located in the space made by the collars 32 between the core and brackets are locking and matrix clamping slide bars 36, 36. 60 These locking and matrix clamping bars 36 are formed with slotted holes in which are located the positioning collars 32. These slotted holes permit the sliding of bars 36 65 by two toggle joints 37, operating on studs

fast in the bars. The toggle joints are united by a slide bar 38 located in bearings formed on cross braces in the core's concavity.

The slide bar 38 of the toggle joint is 70 caused to move longitudinally in its bearings by a hand operating lever 39. This is mounted on a rock shaft 40, located in bearings formed on the brackets 31, 31, and connected to the slide bar 38 by a rock arm 75 41, fast on the rock shaft 40.

It will be seen that the moving of the lever 39 will cause the toggle-joints to expand or contract, thereby moving the slide bars 36, 36 over the straight edges of the 80 core 30 or withdraw them as desired. When a casting chamber is formed by placing the core 30 and its co-acting back 10 in the vertical position the slide bars 36 are moved out over the edges of the core 30 and projections 43, formed on the edges of the bars 36, move into recesses beneath the extensions 18 formed along the adjacent edges of the locking strips 17, and over the packing strip 19, and lock the core and back 90 together throughout their lengths.

The operation of locking the core and back in casting position, also clamps the straight raised bolsters of the matrix M between the bolster packing strip 19 and a 95 slight projection 44 formed on the casting chamber side face of the slide bars 36. During the operation of locking the casting chamber the slide bars 36 engage the projecting ends of the matrix positioning slides 100 22 and force them back out of operative position, as shown in Fig. 8.

The bottom of the casting chamber is closed by a segmental ring 45 provided with the usual bevel and matrix margin recess 105 on the chamber side. This ring 45 is fixed to a short rod 46 movable in a bearing formed through the closed bottom of the core 30. This rod 46 is connected by a link 47 to an arm 48 of a two arm crank fast 110 on a cross shaft 49 which operates in bearings on the brackets 31. The purpose of thus mounting the bottom ring 45 is to move it back from the cast plate and free the bevel cast on the plate from beneath 115 the recessed bevel formed on the ring 45, so that the plate can be lifted free from the core's surface, and recesses J^a (Fig. 2).

The means shown for lifting the plate comprises a series of flanged antifriction 120 rollers 50 which are mounted on the free ends of short arms 51 fast to cross shafts 52, 52 and 49, located in bearings formed on the brackets 31. The three shafts 52, 52, and 49 are caused to operate in unison 125 by a connecting rod 53 attached to short crank arms 54, fast on the shafts 52, 52 and arm 48^a on the two-arm crank fast on the shaft 49.

This plate lifting and bottom ring sepa- 130

rating mechanism is operated to move the bottom ring free from the plate and raise the plate free from the core by a crank arm 55 fast on one end of the cross shaft 49. 5 The loose end of this arm 55 is pivoted to a slide rod 56, which operates through a swivel block 57, mounted in a bearing on cross frame C. A collar 58 fast on the rod 56, near its top pivot, engages the upper 10 surface of the swivel block 57 as the core nears the horizontal position. As the turning of the core continues it forces the crank arm 55 up, which action first starts the bottom ring to move away from the plate's beveled bottom end and then engages the 15 flanged rollers 50 with the straight side edges of the plate. As the movement continues this forces the plate free from the core's surface into the delivery or raised 20 position shown in Fig. 1.

On reversing the core to the vertical position a collar 59, fast on the bottom end of the rod 56, engages the underside of the swivel block, which causes the rollers 50 to 25 move back into the lowered position and the bottom ring into casting position.

The core is turned by a hand lever 60 fast on the front end of the pivot formed on the core supporting yoke 33. A projection 61 30 located on the hub of the lever 60 engages against an adjustable positioning stop 62, fast on the side frame A when the core is turned to its plate delivery position, and aligns the rollers 50 with like rollers 90 35 mounted in bearings formed in the cross frame C. On reversing the core it is stopped in the vertical position by an adjustable stop 63 on a cross brace 64.

The core 30 is provided with recesses J^a 40 for forming projections J on the concave surface of the riser of the plate P.

A thin metal pouring sheet 70 is provided for guiding the metal over the top margin of the matrix M during the casting operation. The pouring sheet 70 is fixed to the 45 concave face of a support 71, which holds the curved sheet 70 vertical at all times. The support 71 is fast to two vertical rods 72, and the rods 72 are supported in bearings 73, fixed on each side frame A and B.

The lower ends of the rods 72 are provided with fixed extending arms 74 carrying antifriction cam rollers 75 located in cam- 50 ways formed in two cams 76 fast on the core pivot shaft 12.

The camways in cams 76 are so shaped that the turning of the back to the vertical position draws the pouring sheet down so its lower curved end will engage the casting 55 side of the top margin of the matrix. After making a cast on reversing the movement, it is withdrawn from between the cast and the margin of the matrix and any fins of metal that may have formed thereinbetween. 60 By mounting the pouring sheet in this man-

ner the operator is not required to handle it in the old ways.

For the purpose of accurately positioning the pouring sheet in relation to the core 30 there are provided positioning pins 77 which 70 are located in extensions formed on the support 71. These positioning pins 77 enter corresponding recesses c' formed on the top end of the core, and hold the core in locked casting position until the sliding bars 86 75 complete the formation of the casting chamber.

The pouring sheet 70 is made on a radius equal to that of the back and of a circumferential length equal to the combined width 80 of the matrix and its raised bolsters. Thus I am able to extend my locking device to the full length of the back and core and thus grip the side edges of the pouring sheet by the same means as I grip the raised bolsters 85 of the matrix.

Owing to the straight ends of the bottom ring 45 engaging against the casting sides of the slide bars 36 instead of beneath the bottom ends of the bars, the ring can be extended up into the casting chamber when a shorter stereotype plate is desired as shown in full lines in Fig. 5.

The camways of the cams 76 are formed so that the pouring sheet's vertical movement takes place during the first half turn 90 of the cams in pivoting the back 10 to the open position.

At the end of the first half turn of the back a pawl 25, pivoted on an extending arm 26, formed on the back's supporting bracket 11, engages a pin 65 fast on the lower end 100 of the core 30, being pressed by a spring 27. As the turning continues the pawl tilts the core on its axis to the position shown in Fig. 105 2. The purpose of thus tilting the core is to place a cast stereotype plate on its periphery in a handy position for the operator standing at the swinging end of the back to reach out and remove the matrix from the type 110 face of the cast plate, and thereafter inspect the same before turning the core and delivering it to the finishing mechanism.

Both the back and core are provided with the usual water cooling chamber. An inlet 115 pipe 80 is located beneath the bottom of the back's chamber and an outlet pipe 81 at one side near the top. (See Fig. 5.) The core inlet 82 is located inside the bottom end wall, and the outlet 83 inside the top cross 120 brace. In operation both the inlet and outlet of the core would be connected with flexible tubing to a source of supply and discharge.

A back operating handle 84 is fast in the 125 longitudinal rib formed on the back's exterior.

Having described the casting features of my invention I will now explain the construction of the finishing mechanism and 130

how the stereotype plate itself starts it through a cycle of operations, how the plate is clamped by the arch, without the axial displacement of the said plate; how the riser 5 is separated from the type portion of the plate, and how it is thereafter disposed of. (See Figs. 9 to 19.)

In describing the casting features we left the stereotype plate P, supported on the 10 flanged rollers 50 and in alignment with rollers 90 operating in brackets formed on the cross frame C. As the plate in this position is free from the core 30 it starts to move down the inclined series of rollers 50 15 engaging with the guide rollers 90 and passes on down until it is located on the guide rollers 91 beneath the arch 101 when it is stopped by projections J on the concave surface of the riser portion of the plate P 20 coming into contact with a positioning stop 149 (see Figs. 10 and 13).

The finishing mechanism is supported between the side frames A and B and cross frames C and D. The arch 101 is mounted 25 on and fast to movable positioning supports 102, 102. The inner faces of the supports 102 are provided with short brackets on which are mounted the set of guide rollers, 91. The supports 102 are located above V 30 shaped projections 103 formed on the top edges of side frames A and B, corresponding V recesses are made in the underside of the supports 102. Each support 102, 102 is made fast to the top ends of two vertical 35 rods 104, operating in bearings formed in brackets 105 and 106, made fast to each upper and inner face of the side frames. The lower ends of the rods 104 are located in bearings 107 fast to the lower inner face of 40 the side frames.

The arch 101 and coating guide rollers 91 and 92 are caused to rise or descend by two pairs of toggle-joints, located between each pair of vertical rods 104. The upper arm 45 108 of each toggle joint is pivoted to fixed brackets, one to bracket 105 and the other to bracket 106, their coating arms 109 are pivoted to cross ties 110, 110 made fast to and joining each pair of vertical rods 104. By 50 thus pivoting the upper arm of the toggle joint to a fixed support and the lower arm to a support made fast to the vertical rods 104 the arch is drawn down by extending the 55 toggle-joints, and raised by contracting the same.

For the purpose of removing the strain from the toggle-joints when raising the arch there are provided four counter-balance springs 111, one of which is wound about 60 each rod 104 between the tops of bearings 107 and collars 112 fast on the rods.

The two sets of toggle-joints are caused 65 to operate in unison by links 113 and 114, which connect the swinging ends of the toggle-joints to the loose end of a vertical

rock lever 115. This lever is fast on a rock shaft 116, which is located in bearings formed in the cross frames C and D. This rock lever 115 is caused to rock back and forth at the beginning and end of each cycle 70 of operations by a cam lever 117, also fast on the rock shaft 116. The swinging end of the lever 117 is provided with an antifriction roller which is positioned in a suitable cam-way formed in a cam wheel 118, mounted 75 on a shaft 119. This cam wheel 118 is caused to make one revolution to each cycle of operations by a worm wheel 120 fast on the end of the cam shaft 119. The worm wheel is driven by a worm 136 located above 80 the worm wheel and fast on a cross driving shaft 137 operating in bearings formed on the cross frame C. Each of the toggle-joint tie pieces 110 is provided at one end with extensions in which are fast vertically disposed and bent rods 121. The top ends of these rods are provided with short studs upon which are mounted guide rollers 92, 92.

In operation the worm wheel 120 makes one revolution to each cycle of finishing operations, first extending the toggle-joints 90 which push down the tie pieces 110 fast on the rods 104, thereby drawing down the arch 101 which engages with the periphery of the stereotype plate. This operation lowers the 95 guide rollers 91 and 92, and deposits the straight edges of the stereotype plate on top of four supports 93, 94 and 162, 162, which are alined with, but slightly below, the top surface of the guide rollers when 100 they are in raised position. The supports 93 and 94 are made L shaped. The top edges of the L supports 93 and 94 act as plate holding means for supporting the plate during the finishing operations. The supports 105 162, 162 are fixed within the opening of the fixed ring support 160 of the trimming mechanism, and are intended to support the riser portion of the plate while it is being separated by the trimming tools as herein- 110 after described.

The L supports 93 and 94 are provided with recesses 124 in which the guide rollers 91 are located. The support 93 is fixed to extending arms formed on the fixed bracket 115 105.

Owing to an uneven shrinkage of the stereotype plates there is a slight variation in the length of its circumference, to compensate which the L support 94 is made 120 slightly movable, and is mounted on arms 95, 95, which are pivoted on studs fast in the ends of the fixed bracket 106. This pivoted L support 94 is held up in the normal lowered position by projections 96, 96 125 formed on the pivot arms 95, engaging against the side frames B, so that it is slightly lower than the upper face of the guide rollers 91, when the rollers are in the raised position as previously stated. But 130

when the guide rollers 91 are lowered, by the lowering of the arch, the plate, as stated, is transferred to the upward projecting arms of the L supports 93 and 94. As the arch 5 nears its lowered operative position a pin 97 fast on the toggle-joint connecting link 114 engages the free end of a stiff spring bar 98 fast to the lower face of the L support 94. This causes the support to swing up and 10 force the curved plate solidly against the dome of the arch 101. Upon the completion of the finishing operations the connecting link 114 reverses its movement when a pin 99, fixed in the link 114, forces the spring bar 98 back and holds the L support 94 down in the lowered position.

The shaving of the ribs formed on the interior of the cast plate is accomplished by a shaving knife 130, mounted on a projecting ledge 131, formed on a hollow knife shaft 132. This knife shaft 132 operates in bearings 133 and 134 formed on top of the cross frames C and D. The knife shaft is revolved by a worm wheel 135 made fast 25 to the end of the shaft, and in front of the bearing 133. This worm gear is located above and in mesh with the driving worm 136, which, as stated, is fast on the cross driving shaft 137, mounted in bearings 30 formed on the face of the cross frame C.

A clutch mechanism is provided and arranged so as to engage and disengage the driving shaft with a constantly driven pulley 138, which is mounted so as to revolve 35 about the front end of the driving shaft 137.

The clutch mechanism I employ is well known in the trade and therefore does not need explaining. The driving member 139 of the clutch is fast to the pulley 138 and 40 the driven member 140 is fast to the driving shaft 137. A yoke 141, pivoted above the shaft member 140 to the cross frame C operates in a groove formed in the shaft member. This yoke 141 is caused to swing back 45 and forth to engage and disengage the clutch members by a spring rod 142, one end of which is pivoted to the yoke and the other end supported in an eye bolt 143, fast in the cross frame C. Mounted on this rod 50 142 in front of the eye bolt is a coil compress spring 144. The spring 144 is held under tension by a collar fast on the rod 142. The function of this spring is to force the clutch members into engagement.

55 A trip mechanism, operated in connection with the shaving knife shaft, causes a trip arm 145 to engage with a pin 146, located in the spring rod and push the rod back against the action of the spring 144 at the 60 end of each cycle of operations. This trip arm 145 is located in a bearing made through the rim of the worm gear 135. The engaging end of this arm 145 is bent down so as to engage in front of the trip pin 146. 65 The opposite end of the arm 145 is fast in

a connecting bracket 147 which is fast on the end of a long rod 148 located in the hollow of the knife shaft 132 and slidably operative in bearings in the ends of said shaft.

70 As previously stated the starting of the finishing mechanism is accomplished by the movement of a stereotype plate into position to be finished. The stereotype plate P is cast with projections J on its concave surface located beneath the riser. These projections J engage in front a stop 149 slidingly mounted on a bearing formed on the knife shaft, and made fast to the end of a slide block 150 operating through a slotted opening in the knife shaft and attached to the long rod 148. A buffer spring 151 is wound about the long rod 148 between the block 150 and the bearing 152 of the rod 148. See Fig. 10.

80 When a stereotype plate is freed from the core 30 it comes gliding down over the core antifriction lifting rollers 50, and over guide rollers 90 and 91, and engages its projections J against the sliding stop 149 with considerable force and pushes the stop back against the action of the buffer springs 151 until the block 150 comes up against the end of the slot in which it operates. At this juncture the stem 153 of a spring latch 154 90 on the slide stop 149 passes beyond the end of the slide stop bearing, and is pushed out by the spring. It engages the edge of the bearing, and holds the stop in the advanced position against the rebound action of the 95 buffer spring. See Figs. 10 and 14.

100 This moving of the slide stop 149 has slid the trip arm 145 from in front of the trip pin 146, leaving the spring 144 free to push the clutch member into engagement and start the mechanism going through its cycle of operations. The driving shaft revolves the worm which in turn revolves both worm gears 120 and 135, causing the arch to come down on top of the plate and the slide stop 110 149 to move around from in front of the projections J on the plate. But when the mechanism is about half through its cycle, as shown in Fig. 14, the end of the stem 153 of the spring latch 154 engages a face 115 cam 155, fast on the underside of the bearing 134, and is pushed back. Whereupon the buffer springs once more come into action and push the long rod 148 back into the starting position and as the cycle nears 120 its end of operations the trip arm 145 once more engages in front of the pin 146 and forces it back thereby disengaging the clutch members and stopping the mechanism.

125 The trimming mechanism for separating the riser from the type face portion of the plate is located in front and axially aligned with the arch 101 when the arch is in the lowered position. The trimming mechanism is mounted on a flanged ring bearing 160 130

fast to the cross frame D by three cap screws 161. See Figs. 1, 9, 10, 12 and 14.

Within the hollow of the ring bearing 160 and at each side are located the fixed 5 plate supports 162, which act to support the riser during the trimming operations. These supports are alined with the L supports 93 and 94 and like them located slightly below and the top level of the guide rollers, when they 10 are in the raised position.

Mounted on the outside of the ring bearing 160 are two toothed rings 163 and 164. Ring 163 is referred to as the tool ring and 164 as the cam ring. The cam ring 164 is 15 located next to the flange of the ring bearing 160, and the tool ring 163 against the cam ring 164. Both rings 163 and 164 are held in position on the ring bearing 160 by the flange of a cover 165 fast to and extending about the periphery of the flange of the ring bearing. These toothed rings 163 and 164 are driven by gear wheels 166 and 167 fast on a shaft 168, operating in bearings in 20 the cross frames C and D. The shaft 168 is driven by a helical gear 169, which is fast on the end of the shaft and located beneath, and in mesh with, a like gear 170, fast on the 25 driving shaft 137.

The tool ring 163 is provided with four 30 movable trimming tools 173 mounted in holders, located on its face and at each quarter of its circumference, and the cam ring 164 with a groove, facing the tool ring, divided into four equally disposed eccentric 35 camways 172, joining each other into a continuous cam groove.

The tool ring 163 is so timed that it makes ten revolutions during each cycle of operations, and the cam ring 164, so that it 40 makes nine and three fourths revolutions during the cycle.

A tool operating cam roller 171 is located 45 in each of the four eccentric camways 172. These are caused to travel from the high point of each eccentric camway to its lowest point and then up a steep incline to the high point of the advance eccentric camway, during each cycle of operations, owing to the tool ring traveling one fourth of a revolution 50 more than the cam ring. (See Fig. 14).

The trimming tools 173 consist of steel bars formed with beveled cutting ends. The tools 173 are each fast in a sliding tool holder 174, which operates in guideways fast 55 to the face of the tool ring 163. Each tool holder is provided with an extension 176 which operates in a slot opening through the tool ring. See Fig. 10. A bearing is formed on the face of the extension 176 60 upon which the cam roll 171 is mounted. See Figs. 10 and 14.

In operation, as the rings are revolved through their cycle the tools advance toward and engage the periphery of the 65 curved plate, and owing to the tools being

positioned to follow each other in sequence in their advancing operations, gradually separate the riser and bevel the edge of the type face portion of the plate.

During the operation of separating the 70 riser from the type portion of the plate the riser is held up by the supports 162, fast within the ring support 160. Just previously the slide stop 149, mounted on the shaving knife shaft 132, has been revolved 75 from in front of the projections J on the riser and the shaving knife 130 has shaved off the ribs cast beneath the type face portion of the plate making the same the proper thickness. As the revolution of the knife 80 shaft continues, the slide stop is brought up into its original position, but to the rear of the projections, J, and leaves the riser free to tip forward over the ends of the fixed supports 162 and slip down through the gap 85 between the cross frame D and the end of a cooling device located in front.

As the riser is now separated and out of the way, the toggle-joint tie piece 110, which supports the two guide rollers 92, 92, moves 90 the rollers up, thus closing the gap through which the riser passed out. Simultaneously with this movement, the arch is raised and the guide rollers lift the now finished stereotype plate off the L supports, leaving it free 95 to glide down the inclined guideway over the antifriction guide rollers 91 and 92, and pass over the rollers 190, on over the top edge of a cooler sink 191 on a set of guide rollers 192. The rollers 190 are mounted in 100 front of the cooler sink and the rollers 192 on studs located within and at each side of the sink. (Figs. 9, 20 and 21.)

The cooling device illustrated comprises the sink 191 fast between the side frames A 105 and B, and located in alinement with the finishing mechanism. Each inside wall of the sink is provided with a set of the flanged guide rollers 192 for supporting a finished stereotype plate, during the cooling operation. Located longitudinally and above the sink 191 is a tube 193, closed at both ends. This tube is supported by brackets 194 and 195 fast to the end walls of the sink. The tube is provided with a slotted opening 196 on its top side. Flexible curved wings 196^a, 196^a are made fast at each side of this slot 196. The free ends of each wing are provided with a stiffening piece 197, 197 on which are extensions 198. 110 Each extension 198 is formed with a slot in which is located a pin 199, fast to the end of four of the flanged guide roller studs. See Fig. 20. The periphery of each flanged guide roller 192 is formed with a slightly 115 flat surface 200, and a bevel surface 201.

Cooling water is admitted to the chamber in the tube 193 through a supply pipe 202, let in through the lower closed end. The water passes out of the tube through the 120 125 130

long slot 196, made in the top side of the tube, and flows down over the curved flexible wings 196^a into the sink out of which it passes through a waste pipe.

5 As stated, a finished stereotype plate glides down from the finishing mechanism over the guide rollers 91, 92 and 190, and over the sink wall on the beveled rollers 192, and over the flexible wings until brought up 10 by a movable stop 203.

When the cooling water comes into contact with the interior surface of the plate, now located over the flexible curved wings, and resting on the flat of the beveled guide 15 rollers 192, the plate's interior begins to shrink, which action causes the straight edges of the plate to draw in; whereupon they leave the flat of the periphery of the guide rollers and move down the bevels, 20 which causes the plate to lower itself upon the curved exterior of the cooler. As the shrinkage continues the flexible wings close in and the straight edges continue to move down the bevel of the rollers. But as the 25 cooling operation progresses through the plate its outside commences to contract and gradually draws the straight edges back up the bevels of the rollers until they once more rest on the flat surface and the plate has 30 returned to its original curvature.

The plate remains upon the cooler guide rollers 192 until the next finishing operation begins, when, through connections with the arch moving mechanism, the movable stop 35 203 is lowered and the plate is free to move off the cooler down the guide rollers 192 and over rollers 204 positioned in recesses formed on two plate receiving brackets 205. It is lifted by the operator from these brackets, 40 all finished and cooled ready to be attached to the printing press cylinders.

The movable stop 203 is supported in a recessed strip 206 fast on the lower end of the cooler sink 191. It is moved up or down 45 by a rock lever 207, fast on a rock shaft 208, operating in bearings formed in the plate supporting and receiving brackets 205. A rock lever 209, fast on the end of the rock shaft 208 is pivoted to one end of a connecting rod 210. The opposite end of this rod is pivoted to a vertically disposed arm 211 of a crank lever, which is mounted on a stud fast in the side frame B. A second arm 212 of the crank lever engages with a pin 213, 55 fast on the adjacent bent guide roller rod 121 which is fast to the tie piece 110 of the adjacent toggle-joint. By thus connecting the movable stop with the toggle-joint tie piece it is caused to move in unison with 60 the up and down movement of the arch. I have not claimed herein the finishing and cooling mechanisms by themselves as they constitute the subject matter of my divisional application on a semi-automatic 65 stereotype plate finishing and cooling ma-

chine, filed August 16, 1919, Serial No. 317,963.

Although I have shown and described a preferred embodiment of the invention, I am aware of the fact that many modifications can be made therein by any person skilled in the art without departing from the scope of the invention as expressed in the claims. Therefore, I do not wish to be limited in these respects, but what I do 75 claim is:—

1. In a curved stereotype plate casting apparatus, the combination of a pivoted back and a pivoted core forming a vertically disposed casting chamber, and means for 80 simultaneously turning the core and back in opposite directions from casting position.

2. In a curved stereotype plate casting apparatus, the combination of a core and back pivoted on different, stationary, parallel axes and forming between them a vertically disposed casting chamber, and means 85 for turning them.

3. In a curved stereotype plate casting apparatus, the combination of a pivoted 90 core, an independently pivoted back provided with a counterbalance, and means for turning the core on its pivot, said core and back being movable to a position to provide a vertical casting chamber. 95

4. In a stereotype plate casting apparatus, the combination of a core pivoted on a stationary axis, a pivoted back, and means for moving the back away from the core to allow the core to turn on its pivot in substantially the opposite direction. 100

5. In a stereotype plate casting apparatus, the combination of a concave back and a convex core, both mounted to swing on parallel fixed axes, with means for turning 105 the core and back.

6. In a stereotype plate casting apparatus, a concave back pivoted at its bottom, and a convex core pivoted on a transverse axis intersecting its convex side, for the purpose 110 set forth.

7. In a stereotype plate casting apparatus, a matrix supporting back, a coacting core, manually operable means on the back for positioning a matrix, and means movably 115 mounted on the core for clamping said matrix in position for the purpose set forth.

8. In a stereotype plate casting apparatus, a matrix supporting concave back having matrix holding means, a convex core having 120 matrix clamping means, movably mounted thereon, and means for moving the clamping means to disengage the holding means.

9. In a stereotype plate casting apparatus, a matrix supporting concave back having 125 matrix holding means, a convex core having matrix clamping means, and means for guiding the clamping means to cause it to disengage the holding means for the purpose set forth. 130

10. In a stereotype plate casting apparatus, the combination with a concave back and a convex core forming a curved casting chamber therein between, of matrix bolster packing strips, matrix holders, locking means attached at each side of the back, matrix clamping means and casting chamber locking means at each side of the core, and means for moving the locking means into engagement to lock the casting chamber and clamp the bolsters of a matrix positioned in the aforesaid chamber between the said packing strips and clamps. 65
11. In a stereotype plate casting apparatus, the combination with a concave back and a convex core forming a curved casting chamber therein-between, of matrix holders, locking means attached at each side of the back, matrix clamping means at each side of the core, and means for moving the locking means to clamp the bolsters of a matrix positioned in the aforesaid chamber. 70
12. In a stereotype plate casting apparatus, the combination of a matrix supporting back, a co-acting core, angularly movable slides on the back for positioning a matrix, and means on the core for clamping said matrix in position. 75
13. In a stereotype plate casting apparatus, the combination of a matrix supporting back and a co-acting core, with a locking strip on one side of the back provided with an angularly disposed guide, and a matrix positioning slide movable along said guide. 80
14. In a stereotype plate casting apparatus, the combination of a back and core forming a curved stereotype plate casting chamber between them, a locking strip on the straight side of the back having an angularly disposed guide thereon, a manually movable matrix positioning slide carried by said guide, and a bar for clamping the matrix and pushing back said slide. 85
15. In a stereotype plate casting apparatus, the combination of a concave back, a convex core co-operating therewith, a locking strip on each straight side of the back, an angularly disposed guide on each locking strip, a pair of movable matrix positioning slides, and a pair of bars for clamping the matrix and pushing said slides back out of matrix positioning location. 90
16. In a stereotype plate casting apparatus, the combination of a pivoted back, an independently pivoted core, means for swinging the core away from the back, and means for giving the core an additional horizontal motion. 95
17. In a stereotype plate casting apparatus, a vertically disposed pivoted back, a counterbalance for the back, a vertically disposed pivoted core, means for moving both back and core from their vertical positions, and means for giving the core an additional horizontal motion for the purpose set forth. 100
18. In a stereotype plate casting apparatus, the combination of a matrix supporting back, a pouring sheet, and means independent of both back and core for supporting the said pouring sheet. 105
19. In a stereotype plate casting apparatus, the combination of a matrix supporting back, a pouring sheet supported independently of the back, and means operated by the back for moving the pouring sheet into or out of operative position. 110
20. In a stereotype plate casting apparatus, the combination of a core, a pouring sheet, a movable support on which said pouring sheet is mounted, and means carried by the support for holding the core in casting position. 115
21. In a stereotype plate casting apparatus, the combination of a matrix supporting back, a core, a pouring sheet, means for separating the back and core to free a plate cast therein-between, and means for moving the pouring sheet longitudinally over the plate for the purpose set forth. 120
22. In a curved stereotype plate casting apparatus, the combination of a back, a core, a pouring piece supported independently of both back and core, means for separating the back and core, and means for turning the casting face of the core away from the pouring piece. 125
23. In a stereotype plate casting apparatus, the combination of a back and core forming a vertically disposed casting chamber, means for holding a matrix at the vertical sides of the casting chamber, means for holding the matrix at the bottom of the chamber, means for holding the top margin of the matrix and guiding molten metal over the same, means for separating the core and back, and means independent of both core and back for supporting the guiding means during and after said separation. 130
24. In a stereotype plate casting apparatus, the combination of a back and movable core forming a vertically disposed casting chamber, a pouring sheet located therein, means for moving the pouring sheet, and means for thereafter moving the core, for the purpose set forth. 135
25. In a curved stereotype plate casting apparatus, a movable back, a core mounted to swing on a fixed axis, a bottom ring and plate lifters carried by the core, and means for moving the ring and lifters to free a plate cast on the surface of the core for the purpose set forth. 140
26. In a stereotype plate casting apparatus, the combination of a back and core forming a casting chamber, means for holding the top margin of the matrix and guiding molten metal over the same, means for 145

separating the core and back, and means independent of the back for supporting the guiding means.

27. In a stereotype plate casting apparatus, the combination of a back and core forming a casting chamber between them, said back being adapted to support a matrix, a pouring sheet, and means independent of the back for supporting said pouring sheet.

28. In a stereotype plate casting apparatus, a back, a core operating on a fixed axis, a bottom ring on the core adjustable longitudinally, and means for moving the ring longitudinally on the core while the core is being turned to a horizontal position.

29. In a curved stereotype plate casting and finishing machine, the combination of a casting back pivoted at one end, a casting core pivotally supported in front of the back, a finishing mechanism located in front

of the core, means for turning the core into alignment with the finishing mechanism, and means for freeing a cast plate from the core and guiding it into the finishing mechanism.

30. In a stereotype plate casting and finishing machine, the combination of a core, upon which a plate is to be cast, a finishing mechanism aligned therewith, a trip mechanism for starting the finishing mechanism, and means for guiding a plate off the core into the finishing mechanism and into engagement with the trip mechanism for the purpose set forth.

In testimony whereof I have hereunto set my hand, in the presence of two subscribing witnesses.

CHARLES E. HOPKINS.
